SCREEN

Loren G. Symons, Hollywood, Calif., assignor, by
mesne assignments, to Nordberg Manufacturing
Company, Milwaukee, Wis., a corporation
of Wisconsin

Application June 12, 1935, Serial No. 26,233

17 Claims. (Cl. 209—329)

My invention relates to an improvement in screens or material separating devices and has for one purpose the provision of a screen which shall be economical to manufacture, easy to operate, durable and highly efficient in operation. Another object is the provision of improved means for supporting a vibratory screen deck. Another object is the provision of improved means for supporting the vibrating means of a vibrating screen. Another object is the provision of improved means for limiting and controlling the vibrating means of a vibrating screen. Other objects will appear from time to time in the course of the specification and claims.

15 I illustrate my invention more or less diagrammatically in the accompanying drawings, wherein—

Figure 1 is a partial plan view of my invention;

20 Figure 2 is a side elevation with parts broken away and parts in section;

Figure 3 is an enlarged section taken on the line 3—3 of Figure 2;

Figure 4 is a section taken on the line 4—4 of 25 Figure 3; and

Figure 5 is a section taken on the line 5—5 of Figure 3.

Like parts are indicated by like symbols throughout the specification and drawings.

30 Referring to the drawings, 1 generally indicates any suitable base which may, for example, be formed by generally parallel side members indicated as 2. Any suitable transverse supports or connections indicated as 3 may be employed.

35 5 generally indicates any suitable screen deck. The deck is not indicated in great detail as a variety of screen decks may be employed. As means for mounting the screen deck 5 upon the base or support 1, I provide a plurality of upwardly inclined springs generally indicated as 6. I illustrate each spring 6 as composed of a plurality of laminations 6a, clamped for example by clamps 6b, intermediate their ends. These laminations are preferably not over $\frac{1}{16}$ " in thickness

40 and the clamps 6b are indicated illustratively rather than as limiting me to the particular spring disposition shown. The springs 6 are associated with and are bolted to angles 7 and 8 which may be welded or otherwise secured to the support 1 and the screen deck 5 respectively. 9 indicates any suitable bolts with nuts 10 which engage suitable spring clamp plates 11. The flanges 11a of the angles 7 and 8 serve as spacers 45 between the adjacent pairs of springs 6.

15 indicates any suitable screen cloth but the attachment of the cloth to the deck 5 is not shown in detail as it does not of itself form part of the present invention. It will be understood that I may employ screen cloth or any other suitable 5 perforated or apertured screening member or surface, secured to the deck 5 in any suitable manner.

10 In order to hold the springs 6 to a predetermined neutral position I provide additional yielding means at either side intermediate the support 1 and the screen deck 5. I illustrate, for example, a bracket 20 on the deck 5 and a corresponding bracket 21 on the support 1. Passing through the aperture 22 of the bracket 20 is the 15 reduced end of the pin or guide 23. It is locked in position in relation to the bracket 20, as by any suitable nut 24. The opposite end of the pin 23 passes through the aperture 25 of the bracket 21. Positioned about the pin 23 on opposite sides 20 of the bracket 21 are coil springs 26, 27, which are compressed between the washers 28, 29, and the nuts 30, 31. The effect of this yielding connection between the deck 5 and the support 1 is to constrain the deck to a predetermined neutral position, which is preferably the position 25 shown in Figure 2 with the springs 6 unflexed. However, the springs 26, 27, have such strength as to permit vibratory movement of the deck 5 in response to the rotation of the vibrating means 30 below described. The compression of the springs may be adjusted, by tightening or loosening the nuts 30 or 31.

35 In order to impart vibration to the deck 5 I may employ an unbalanced member. I illustrate, however, a particular type of unbalanced member which I find highly advantageous and which is claimed herein. It will be understood that I do not wish to be limited to the use of this particular unbalanced member, however, in connection with my screen.

40 In reference to the particular unbalanced member herein shown and claimed, I illustrate a bearing sleeve generally indicated as 35 which is provided at opposite sides with flat webs 36 to 45 which may be bolted springs 37, 38 respectively, on opposite sides of the axis of rotation of the rotor. These springs, formed of thin laminae, may be bolted in position as by the employment 50 of clamping plates 39, bolts 40 and nuts 41. The opposite ends are clamped between any suitable brackets 42, clamp plates 43, bolts 44, and nuts 45. It will be observed from Figure 1 that the springs 37 and 38 are generally parallel and that 55

they are both secured in relation to the screen deck itself.

I find it preferable, although not absolutely necessary, to have the springs 37 and 38 generally perpendicular to the deck supporting springs 6. For additional supporting means for the vibratory structure, whereby the springs 37, 38 are held normally in the neutral position in which they are shown in Figure 2, I provide at both bearing sleeves 35 a pin 50 secured to the lower web 36. It passes through the apertured bracket 51 on the screen deck and is provided with coil springs 52, 53, located on opposite sides of said bracket and held under compression as by washers 54, 55, and adjustable nuts 56, 57. The structure just described serves as an additional supporting means for holding the vibrating mechanism in the position in which it is shown in Figure 1, while still permitting its flexure in response to the rotation of the below described unbalanced member.

The rotor itself includes the shaft 60 provided with any suitable pulley 61 about which may pass the belt 62 to any suitable motor or power source 63. 64 indicates an inner ball race about the shaft 60 and 65 an outer ball race within the member 35. 66 indicates any suitable balls or rollers whereby the shaft 60 is permitted to rotate freely with a minimum of friction within the sleeve 35. 67 is one member of any suitable dust excluding labyrinth or seal and 68 the opposite member. It will be understood that the member 67 rotates with the shaft 60, whereas 68 is fixed in relation to or forms part of the member 35. It will be realized that any other suitable means for excluding dust or confining lubricant may be employed. 69 is an inner end plate associated with the end member 70 to which the cylindrical housing portion 71 may be secured in any suitable manner, for example, by welding. The result is a tightly closed housing with no room for access of dust. It will be understood that whereas I have described but one end of the vibrating mechanism, both ends 45 may be identically formed.

Rotating with and as a part of the shaft 60 is the square central portion 75 which extends substantially throughout the length of the housing 71. Secured to it is a shorter fixed member 50 76, herein shown as spaced centrally of the square central portion and having outwardly extending shoulders 77 which may be apertured as at 78 to permit the passage therethrough of limit bolts 79 the length of which may be adjusted as by nuts 80, fitting in pockets 81 in the outer face of the member 76. The bolts 79 are provided with limit heads 82. 83 indicates compression springs surrounding the bolts 79 and compressed between the heads 82 and the bottom surface 84 of pockets or apertures 85 formed in side members 86. The side members 86, of which two are shown, are connected to the cross members 87 and 88. It will be understood that the members 86, 87 and 88 may be integral 65 or secured together by the pins 90 with heads 91 and adjustable nuts 92 so that they move as a unit. The side members 86 and the cross member 87 extend substantially throughout the length of the housing 71, whereas the smaller 70 cross members 88 may be secured at either end of the members 86, as illustrated in Figures 1 and 3. The cross members 88 are preferably spaced from the members 86 by spacing bars 89 of predetermined thickness, which determine the 75 clearance 89a between the square shaft 75 and

the cross bars 88. It will be understood that the strength of the springs 83 is such that when the rotor is at rest the parts are normally in the position in which they are shown in Figures 4 and 5. When the motor is driving the rotor through the pulleys 61 and when a predetermined speed of rotation is reached, then the centrifugal tendency of the member 87, with its attached members 86, overcomes the force of the springs 83 and moves outwardly from the center of rotation of the shaft 60. The parts are so proportioned that when the springs 83 hold the parts in the position of Figure 5 the rotor is in dynamic balance and will rotate without causing any vibration. When the speed increases sufficiently to cause the members 86, 87, 88 and 89 to move centrifugally outwardly from the axis of rotation of the rotor, the member then becomes unbalanced, and, in response to its rotation, vibrates and causes a vibration of all attached parts including the screen deck 5. The clearance 89a obtained by the spacing members 89, limits the distance the members 86, 87 can move outwardly from the axis of the rotor 75.

The rate of rotation necessary to cause this unbalance may be determined, controlled and adjusted by setting the nuts 80 in order to increase or diminish the compression on the springs 83.

It will be understood that the spacing members 89 may be replaced by similar spacing members of more or less thickness in order to vary the clearance 89a which defines the possible movement of the member 87, away from the center of rotation of the shaft 60 and away from the opposite fixed member 76. Thus I can, by setting the springs 83, limit or control the speed of rotation necessary to cause unbalance, and by varying the thickness of the 40 spacing members 89 I can limit the possible maximum unbalance permitted.

It will be realized that whereas I have described and shown a practical and operative device, nevertheless many changes might be 45 made in the size, shape, number and disposition of parts without departing from the spirit of my invention. I therefore wish my description and showing to be taken as in a broad sense illustrative and diagrammatic rather than as limiting me to my specific showing.

The use and operation of my invention are as follows:

I find it desirable to mount my rotor upon leaf springs as they form a very advantageous 55 connection between the rotor and the screen deck. When the device is out of use, however, it is important to provide additional supporting means, to prevent undesired flexure of the springs 37, 38. I find the pin or pins 50 in connection with the springs 52 and 53 an adequate solution of this problem. It has the further advantage of providing a further limit and control of the amplitude of vibration of the springs 37, 38, in response to rotation of the rotor, particularly at low speeds when the device is being stopped.

I find it preferable to have the springs 37, 38, perpendicular to the springs 6 but this is not absolutely necessary and I wish my claims to 70 be interpreted with sufficient scope to cover a substantial deflection from such perpendicularity. I further find it an efficient solution to have the unbalanced rotor positioned above the screen deck and intermediate the ends of the 75

screen deck. This again is to some extent a matter of convenience and my screen will operate with the unbalanced rotor positioned beyond the end of the deck.

5 I claim:

1. In a vibrating screen, a support, a screen deck, yielding supporting means intermediate said support and said deck, including a plurality of parallel leaf spring members positioned at a plu-

10 rality of points along the opposite sides of said screen deck, and means for vibrating said deck, including an unbalanced rotor and means for rotating it about a horizontal axis extending transversely across the line of movement of the

15 screen, bearing means for said rotor and a flexible supporting connection between said bearing means and the screen deck, including a plurality of leaf spring members secured to opposite sides of said screen deck, said last mentioned spring

20 members being generally perpendicular to the spring supporting members intermediate the deck and the support.

2. In a vibrating screen, a support, a screen deck, yielding supporting means intermediate said support and said deck, including a plurality of parallel leaf spring members positioned at a plu-

25 rality of points along the opposite sides of said screen deck, and means for vibrating said deck, including an unbalanced rotor and means for

30 rotating it about a horizontal axis extending transversely across the line of movement of the screen, bearing means for said rotor and a flexible supporting connection between said bearing

35 means and the screen deck, including a plurality of leaf spring members secured to opposite sides of said screen deck, said last mentioned spring members being generally perpendicular to the spring supporting members intermediate the deck and the support, the leaf spring members be-

40 tween the unbalanced rotor and the screen deck being located some on one side and some on the opposite side of the axis of rotation of said rotor.

3. In a vibrating screen, a support, a screen deck, yielding supporting means intermediate said support and said deck, including a plurality of parallel leaf spring members positioned at a plu-

45 rality of points along the opposite sides of said screen deck, and means for vibrating said deck, including an unbalanced rotor and means for

50 rotating it about a horizontal axis extending transversely across the line of movement of the screen, bearing means for said rotor and a flexible supporting connection between said bearing

55 means and the screen deck, including a plurality of leaf spring members secured to opposite sides of said screen deck, said last mentioned spring members being generally perpendicular to the spring supporting members inter-

60 mediate the deck and the support, the leaf spring members between the unbalanced rotor and the screen deck being located some on one side and some on the opposite side of the axis of rotation of said rotor, there being a pair of such members adjacent each side of the screen deck.

65 4. In a vibrating screen, a support, a screen deck, yielding supporting means intermediate said support and said deck, including a plurality of parallel leaf spring members positioned at a plu-

70 rality of points along the opposite sides of said screen deck, and means for vibrating said deck, including an unbalanced rotor and means for rotating it about a horizontal axis extending transversely across the line of movement of the

75 screen, bearing means for said rotor and a flexible

supporting connection between said bearing means and the screen deck, including a plurality of leaf spring members secured to opposite sides of said screen deck, said last mentioned spring members being generally perpendicular to the spring sup- 5 porting members intermediate the deck and the support, and being inclined upwardly somewhat from the plane of the deck, the unbalanced rotor being located above said deck.

5. In a vibrating screen, a support, a screen deck, yielding supporting means intermediate said support and said deck, including a plurality of parallel leaf spring members positioned at a plu-

10 rality of points along the opposite sides of said screen deck, and means for vibrating said deck, including an unbalanced rotor and means for rotating it about a horizontal axis extending transversely across the line of movement of the

15 screen, bearing means for said rotor and a flexible supporting connection between said bearing 20 means and the screen deck, including a plurality of leaf spring members secured to opposite sides of said screen deck, said last mentioned spring members being generally perpendicular to the

25 spring supporting members intermediate the deck and the support, and being inclined upwardly somewhat from the plane of the deck, the unbalanced rotor being located above said deck, and intermediate its ends.

6. In a vibrating screen, a support, a screen 30 deck, supporting leaf springs intermediate said support and said deck, a rotary unbalanced mem- 35 ber supported on said screen deck, and supporting leaf springs therefor, intermediate said rotary member and said deck, the leaf springs interme-

35 diate the housing and the screen deck being generally perpendicular to the leaf springs intermediate the screen deck and the support, and yield-

40 ing means between the screen deck and the sup- 45 port and between the screen deck and the rotary unbalanced member respectively, tending respec- tively to move said screen deck into a predetermined neutral position in relation to the support and to move said rotary unbalanced member into a predetermined position in relation to the screen

50 7. In a vibrating screen, a support, a screen deck, yielding supporting means intermediate said

55 screen deck and support, a rotary unbalanced member supported on said screen deck, means 50 for rotating it, supporting leaf springs therefor intermediate said rotary member and deck, and additional yielding supporting means between the rotary member and the screen deck, adapted to permit flexure of the leaf springs, but tending 55 to move the rotary unbalanced member and leaf springs into a predetermined position in relation to the screen deck.

8. In combination, a flexibly mounted screen, an unbalanced rotatable member, means for ro- 60 tating it about a horizontal axis extending trans- versely across the line of movement of the screen, bearings therefor, and a supporting connection between said bearings and said screen including a plurality of flexible leaf spring connections, 65 said connections being inclined somewhat in relation to the screen, said unbalanced rotatable member being positioned out of the plane of the screen.

9. In combination, a flexibly mounted screen, 70 an unbalanced rotatable member, means for ro- tating it about a horizontal axis extending trans- versely across the line of movement of the screen, bearings therefor, and a supporting connection between said bearings and said screen including 75

- a plurality of flexible leaf spring connections, said connections being inclined somewhat in relation to the screen, said unbalanced rotatable member being positioned out of the plane of the screen, and an additional yielding connection between the bearings of said unbalanced member and the screen, effective to permit flexure of said first mentioned flexible leaf spring supporting connections.
10. In combination, a flexibly mounted screen, an unbalanced rotatable member, means for rotating it, bearings therefor, and a connection between said bearings and said screen including a plurality of flexible leaf spring connections, said connections being inclined somewhat in relation to the screen, said unbalanced rotatable member being positioned out of the plane of the screen, and an additional yielding connection between the bearings of said unbalanced member and the screen, effective to permit flexure of said first mentioned flexible leaf spring connections, and including a stem extending intermediate said bearings and screen, and yielding means associated with said stem, tending to move said unbalanced member to a predetermined position in relation to the screen.
11. In a vibrating screen, a support, a screen deck, yielding leaf springs intermediate said support and said screen deck, a rotary unbalanced member supported on said screen deck, a housing thereabout, and leaf springs, intermediate said housing and said screen deck, the leaf springs intermediate the housing and the screen deck being generally perpendicular to the leaf springs intermediate the screen deck and the support, and means tending to limit the flexure of the leaf springs supporting said housing.
12. In a vibrating screen, a support, a screen deck oscillatably mounted on said support, and means for vibrating said screen, including an unbalanced rotor mounted for rotation about a horizontal axis extending transversely of the path of movement of the screen, bearing means for said rotor, and a flexible supporting connection between said bearing means and the screen deck, including a plurality of leaf spring members secured to opposite sides of the screen deck in pairs, one leaf spring of each pair being secured to said bearing means above the axis of rotation of the unbalanced member, and one below.
13. In a vibrating screen, a support, a screen deck oscillatably mounted on said support, and means for vibrating said screen, including an unbalanced rotor mounted for rotation about a horizontal axis extending transversely of the path of movement of the screen, bearing means for said rotor, and a flexible supporting connection between said bearing means and the screen deck, including a plurality of leaf spring members secured to opposite sides of the screen deck in pairs, one leaf spring of each pair being secured to said bearing means above the axis of rotation of the unbalanced member, and one below, and additional yielding means, interposed between the bearing means for the rotor and the screen deck,

for limiting the flexure of said leaf spring members.

14. In a vibrating screen, a support, a screen deck oscillatably mounted on said support for oscillation in a generally arcuate path, and means for vibrating said screen, including a rotor mounted for rotation about a horizontal axis extending transversely of the path of movement of the screen, and a flexible supporting connection between said rotor and the screen deck whereby said rotor can oscillate, in relation to said deck, in a generally arcuate path, the tangents of the path of oscillation of the deck in relation to its support and of the path of oscillation of the rotor in relation to the deck being substantially perpendicular to each other.

15. In a vibrating screen, a support, a screen deck oscillatably mounted on said support for oscillation in a generally arcuate path, and means for vibrating said screen, including a rotor mounted for rotation about a horizontal axis extending transversely of the path of movement of the screen, and a flexible supporting connection between said rotor and the screen deck whereby said rotor can oscillate, in relation to said deck, in a generally arcuate path, the tangents of the path of oscillation of the deck in relation to its support and of the path of oscillation of the rotor in relation to the deck being at a substantial angle to each other.

16. In a vibrating screen, a support, a screen deck oscillatably mounted on said support for oscillation in a generally arcuate path, and means for vibrating said screen, including a rotor mounted for rotation about a horizontal axis extending transversely of the path of movement of the screen, and a flexible supporting connection between said rotor and the screen deck whereby said rotor can oscillate, in relation to said deck, in a generally arcuate path, the tangents of the path of oscillation of the deck in relation to its support and of the path of oscillation of the rotor in relation to the deck being at a substantial angle to each other, the supporting means for the screen deck, and for the rotor, including leaf springs.

17. In a vibrating screen, a support, a screen deck oscillatably mounted on said support for oscillation in a generally arcuate path, and means for vibrating said screen, including a rotor mounted for rotation about a horizontal axis extending transversely of the path of movement of the screen, and a flexible supporting connection between said rotor and the screen deck whereby said rotor can oscillate, in relation to said deck, in a generally arcuate path, the tangents of the path of oscillation of the deck in relation to its support and of the path of oscillation of the rotor in relation to the deck being at a substantial angle to each other, the supporting means for the screen deck, and for the rotor, including leaf springs, the supporting springs intermediate the rotor and deck being generally perpendicular to the supporting means intermediate deck and support.

LOREN G. SYMONS.
